UNITED STATES PATENT OFFICE.

ARTHUR DARE, OF PHILADELPHIA, PENNSYLVANIA.

DEVICE FOR MUFFLING SOUNDS.

1,081,490.

Specification of Letters Patent.

Patented Dec. 16, 1913.

Application filed March 15, 1912. Serial No. 684,059.

To all whom it may concern:

Be it known that I, ARTHUR DARE, a citizen of the United States, residing at the city of Philadelphia, in the county of Philadelphia and State of Pennsylvania, have invented certain new and useful Improvements in Devices for Muffling Sounds, of which the following is a specification.

My invention relates to improvements in devices for reducing or muffling sound, particularly such sounds as may be caused by the human voice, and the primary object of my invention, therefore, is to render sound produced by the human voice indistinct or incoherent outside of the transmitter of a telephone or other instrument into which sound waves may be directed or be developed. Thus, for instance, in telephone service, two persons may be sitting in proximity to each other and one may talk into the transmitter of the telephone instrument without the other being able to understand what is being said, while, at the same time, the spoken message will be clearly and distinctly transmitted to a person in line of communication with the instrument.

My present invention embodies improvements in addition to those described and claimed in Letters Patent granted to me December 22nd, 1908, No. 907,320.

The various features of novelty which characterize my invention are pointed out with particularity in the claims connected to and forming a part of the specification, for a better understanding of which, however, and the advantages possessed by it, reference may be had to the accompanying drawings and descriptive matter, in which I have illustrated and described one of the forms in which my invention may be embodied.

Of the drawings:—Figure 1 illustrates an elevation of a telephone transmitter constructed and arranged according to my invention. Fig. 2 represents a side elevation of the same. Fig. 3 is an enlarged front elevation of the mouth-piece. Fig. 4 is a vertical section of the mouth-piece, the section being taken on line 4—4 of Fig. 3, and Fig. 5 represents a transverse section on line 5—5 of Fig. 4.

The mouth piece comprises a cylindrical casing A, provided with a detachable cover A¹ to which is threaded a flaring extension A² fashioned to cover the lips and a portion of the face of the operator. The casing A is also provided with a diaphragm B, which

covers a sound discharge passage A³, said diaphragm being secured to the casing by suitable springs B², held in place by binding screws B¹. Sound waves, together with exhaled air admitted to the flaring extension A² pass through a series of openings a², a², etc., in the detachable cover A¹ and the exhaled air produced in talking is permitted to escape through an exhaust passage A⁴.

In order to render sound produced in any manner, but particularly sound produced by the human voice, indistinct or incoherent as it is carried by exhaled air through the exhaust passage A⁴, I provide said exhaust passage with an exhaust head or muffler C, as more clearly illustrated in Fig. 4. The exhaust head C comprises a tube threaded to the casing at a point C¹ and having bifurcated discharge passages c² and c³ terminating in oppositely disposed openings c¹² and c¹³, between which is a slit or narrow air-gap for the discharge of air.

The device thus described may be attached directly to the transmitter of a telephone of ordinary construction by means of suitable connections. I prefer, however, to employ connections such for example as those illustrated in Figs. 1 and 2 of the drawings which I will now proceed to describe. The casing A, is provided with a threaded nipple a to receive a correspondingly threaded coupling D, fitted also to receive one or more non-resonant tubes D¹ and D².

In ordinary practice I prefer to employ two tubes as shown in Fig. 2, which tubes are preferably made of india-rubber of any convenient caliber and length. The tubes D¹ and D² are in turn connected to terminals D¹¹ and D¹², comprising tubes having slightly flared ends as shown by dotted lines in Fig. 2, and these tubes are fastened to a ring D³, detachably secured to a transmitter D⁴, which represents the mouth piece of a telephone of ordinary construction.

In some instances the diaphragm B may be dispensed with, permitting a clear passage between the casing A and the transmitter D⁴, or the casing A, together with its extension A², and the exhaust-head C may, if desired, be connected direct to a telephone instrument in lieu of the transmitter D⁴. I prefer, however, for telephone service, to employ the construction shown in its entirety, particularly the diaphragm B, which serves as a means to further muffle

sound, as also to prevent the accumulation and condensation of moisture in the tubes and connections leading to the telephone proper.

5 Having thus described my invention, what I claim is:—

1. A sound transmitting device, comprising a casing provided with a mouth piece and a sound discharge passage, a muffler 10 mounted upon the casing and provided with oppositely disposed discharge orifices, a diaphragm arranged within the casing, spring means for adjusting the tension of the diaphragm and one or more tubes leading 15 from the discharge passage to a sound transmitting mechanism.

2. A sound transmitting device comprising a casing provided with a mouth piece and a sound discharge passage, an exhaust-head mounted upon the casing and provided with 20 oppositely disposed discharge orifices, and one or more non-resonant tubes leading from the casing to the mouth piece or horn of a telephone instrument, substantially as described.

25 In testimony whereof I hereto affix my signature in presence of two witnesses.

ARTHUR DARE.
